(57) **CLAIM**

The ornamental design for a portion of a hand tool, as shown and described.

DESCRIPTION

FIG. 1 is a perspective view of a portion of a hand tool according to our new design;

FIG. 2 is a left side elevation view thereof;

FIG. 3 is a right side elevation view thereof;

FIG. 4 is a top plan view thereof;

FIG. 5 is a bottom plan view thereto;

FIG. 6 is a rear elevation view thereof;

FIG. 7 is a front elevation view thereof; and,

FIG. 8 is a right side elevation view thereof, shown in the environment of a complete hand tool, shown in a closed configuration.

The broken lines immediately adjacent the shaded areas represent bounds of the claimed design and environment while all other broken lines are directed to environment and are for illustrative purposes only. The broken lines form no part of the claimed design.

1 Claim, 5 Drawing Sheets
